UNITED STATES PATENT OFFICE.

FRED. W. GORDON, OF PITTSBURG, PENNSYLVANIA.

BELL AND HOPPER MECHANISM FOR BLAST-FURNACES.

SPECIFICATION forming part of Letters Patent No. 298,370, dated May 13, 1884.

Application filed October 22, 1883. (No model.)

To all whom it may concern:

Be it known that I, FRED. W. GORDON, of Pittsburgh, Allegheny county, Pennsylvania, have invented certain new and useful Improvements in Bell and Hopper Mechanism for Blast-Furnaces, of which the following is a specification.

This invention pertains to improvements in the ordinary bell and hopper mechanism for the tops of blast-furnaces.

The invention relates to the raising and lowering devices, as hereinafter fully set forth.

In the accompanying drawings, Figure 1 is a vertical section of the top of a blast-furnace provided with my improved bell and hopper mechanism. Fig. 2 is a plan of the same; Fig. 3, a vertical section of the crab-stand at the tail of the bell-lever, and Fig. 4 a horizontal section of the crab-stand.

In the drawings, A represents the top portion of a blast-furnace; B, the hopper-casting, constructed as usual; C, the bell, fitted to operate in connection with the hopper in the usual manner; D, the charging-platform around the top of the furnace; E, the extension of the top platform toward the hoist-house; F, the suspending-rod to which the bell is attached; G, the supporting-pin by which the bell-rod is attached at the apex of the bell, the apex of the bell being slotted, and the pin being passed through the jaws thus formed and through the eye of the rod; H, a high thin arch supported on the furnace-top and springing over the hopper, it being arranged, preferably, in the line of the extension of the platform toward the hoist-house; I, a pair of rods attached to the bell, guided through holes in the arch, and provided with enlargements at their upper ends; J, cushion-springs around the rods I above the arch; K, the bell-lever pivoted to the arch; L, a wrist-block fitted upon the bell-rod sufficiently loose to slide therein; M, the side links connecting the head of the bell-lever with the wrist-block; N, keys through the bell-rod at the top and bottom of the wrist-block; O, a mortise through the bell-rod at a point lying directly over the arch when the bell is up; P, a series of mortises in the bell-rod below the wrist-block; Q, the counterbalance-box on the tail of the bell-lever; R, the fender for the topman's protection; S, a cylindrical weight hung to the tail of the bell-lever; T, rack-teeth in the cylindri-

cal weight; U, the crab-stand, being a casting bored to fit the cylindrical weight which slides through it, and fitted to sustain the operating mechanism; V, the crank-wheel for operating the weight; W, the lock-lever of the crab-stand; X, a pinion upon the shaft of the hand-crank engaging the teeth of the cylindrical weight; Y, a friction-pad seated loosely in a recess in the bore of the crab-stand, and fitting the surface of the cylindrical weight, and Z an eccentric portion of the shaft of the lock-lever bearing against the back of the friction-pad.

The cylindrical weight is constructed of considerable size, and forms a portion of the counter-balance of the bell, but its functions are hereinafter set forth, and do not essentially require that it shall act as such counter-balance. It will, however, be spoken of in the description as a "weight."

The weight may be raised and lowered through the crab-stand by means of the hand-crank in an obvious manner. When the lock-lever, which is provided with an adjustable heavy weight, is thrown into the position represented by dotted lines in Fig. 3, the friction-pad will be held against the cylindrical weight with great force, and the weight will be thereby firmly retained in any position in which it may be set. If the lock-lever be thrown backward in the position indicated in Fig. 1, the friction-pad will be free and the weight is at liberty to be moved up or down through the crab-stand by means of the hand-crank, or by means of the other forces naturally applied to it. The counterbalancing-weight at the heel of the bell-lever is arranged to slightly overbalance the bell, whereby the bell is normally held in a closed position, as shown in Fig. 1.

In the operation of charging the furnace the lock-lever is thrown forward, so as to prevent the weight from rising through the crab-stand. The charge is then dumped into the hopper. The lock-lever is then thrown forward, and the weight of the charge upon the bell causes it to descend and discharge its load, after which it automatically rises to a closed position, when the lock-lever is to be again thrown forward preparatory to the dumping of the new charge into the hopper. The crank-wheel and rack-and-pinion arrangement permits the bell to be operated without being charged. The pin G, uniting the bell-rod to the bell, is entirely exter-

nal to the bell, and in case any renewal of parts is rendered necessary by accident, such renewal may be effected without inconvenience, which is not the case where the bell-rod attachment is dependent upon devices within the bell, and the jaws each side of the rod-eye serve to protect the foot of the rod from the action of the sulphurous gases. The rods I serve to prevent the dropping of the bell in case of breakage of the bell-rod, and also serve, through the medium of the springs J, to cushion it at the end of its fall, whether its fall be the usual descent in operation or its accidental descent upon the breaking of its rod.

15 I make provision for utilizing the mechanism as a handling device in the removal of the bell or hopper and in the insertion of new ones. When the bell is up, as shown in Fig. 1, a pin is put through the hole O in the bell-rod over the arch. Keys N are then withdrawn and the tail of the bell-lever lifted by the hand-crank, whereby the wrist-block becomes moved some distance down upon the bell-rod, the bell being in the meantime supported by the pin above the arch. A key can now be inserted over the wrist-block in one of the mortises P. Depressing the tail of the bell-lever will now lift the bell and hopper upward from the throat of the furnace a sufficient distance to permit the pin 25 above the arch to be put through one of the lower mortises, which has appeared above the arch, after which the operation may be repeated, a new hitch being taken upon the bell-rod each time until the bell and hopper are lifted 30 sufficiently high to permit bars to be laid under them across the top of the furnace, after which they may be slid out through the arch, and new ones brought in.

35 The construction of the weighted rack S in the form of a cylinder permits of simple fitting in the crab-stand and at the friction-pad. As a matter of course, this rack may have any section desired, the crab-stand and the friction-pad being arranged to suit.

I claim as my invention—

1. In a blast-furnace, a bell, a hopper, an arch over the throat of the furnace, a lever for operating the bell, a rod attached to the bell and reaching upward through an eye in the arch, a mortise and pin or equivalent arrangement at the rod above the arch, for supporting the bell independent of the lever mechanism, and a connection between the lever and the rod fitted to take hold of the rod at different points in its length, combined substantially as set forth, for the purpose of enabling the bell-lifting mechanism to be used in removing the hopper.

2. In a blast-furnace, a bell and hopper, an arch over the throat of the furnace, a lever to operate the bell, a rod connecting the lever with the bell, and one or more rods independent of said connecting-rod provided with enlargements at their upper ends attached to the bell and engaging through eyes in the arch, combined substantially as set forth, for the purpose of supporting the bell in its open position when the connection between the bell and lever is broken.

3. In a blast-furnace, the combination of a bell and hopper, a lever for operating the bell, a vertically-arranged rack hung to the tail of the lever, a crank-wheel and pinion engaging said rack, friction-pad engaging said rack, an eccentric engaging the friction-pad, and a weighted lever to said eccentric, substantially as and for the purpose set forth.

4. In a blast-furnace, the combination of a feed-hopper, bell, and operating-lever with the cylindrical weight S, having teeth T, the crab-stand U, fitting the cylindrical weight, the crank and pinion V X, the friction-pad Y, the weighted lock-lever W, and the eccentric Z, substantially as and for the purpose set forth.

FRED. W. GORDON.
